(57) **CLAIM**

The ornamental design for a shoe upper with saddle, as shown and described.

DESCRIPTION

FIG. 1 is a perspective view of the shoe upper with saddle showing our new design;

FIG. 2 is a second perspective view thereof;

FIG. 3 is a left side elevational view thereof;

FIG. 4 is a right side elevational view thereof;

FIG. 5 is a rear elevational view thereof; and,

FIG. 6 is a front elevational view thereof.

The different amount of shading on the saddle pieces are intended to show separate pieces and do not represent any particular color or colors.
